BLOCK MAKING MACHINE

Joseph J. Holland, Jr., Greenville, Miss.

Application January 12, 1938, Serial No. 184,701

7 Claims. (Cl. 25—41)

This invention relates to machines for making building blocks and an object of the invention is to provide a machine of this character through the medium of which building blocks may be quickly and expeditiously made.

A further object of the invention is to provide a machine embodying improved means for feeding the material from which the block is to be made to a mold; as well as improved means for 10 vibrating the mold during the feeding of the material thereto.

A further object of the invention is to provide a machine of this character embodying a novel arrangement of feed hopper, mold, and vibrator; as well as improved means for controlling the feeding of the material from the hopper to the mold.

The invention together with its objects and advantages will be best understood from a study of 20 the following description taken in connection with the accompanying drawings wherein:

Figure 1 is a top plan view of the machine.

Figure 2 is a view partly in section and partly in elevation illustrating certain details herein- 25 after more fully referred to.

Figures 3 and 4 are detail views taken substantially on the lines 3—3 and 4—4 respectively of Figure 2.

Figure 5 is a fragmentary detail view with cer- 30 tain parts in section and showing the vibrator.

Figure 6 is a fragmentary detail view partly in section and partly in elevation illustrating cer- 35 tain parts of a raising and lowering device for the mold.

Figure 7 is an enlarged view partly in section and partly in elevation showing a core member positioned within the mold.

Figure 8 is a top plan view of the mold.

Figure 9 is an enlarged fragmentary sectional view through the mold, the latter being shown in 40 lowered position and

Figure 10 is a perspective view of the building block.

Referring to the drawings by reference numerals it will be seen that the device is particularly designed for making or forming building blocks of the type suggested in Figure 10 and indicated by the reference numeral 5, said blocks being formed of suitable material and shown as 50 being provided at the opposite ends thereof with grooves 6 and intermediate the grooved ends 6 with through openings 7.

In the preferred embodiment thereof the block making machine comprises a base 8 from which 55 rises a pair of tubular standards 9 that telescop-

ically receive therein rods 10. The rods 10 at their upper ends are connected by a cross member 11. Integral with the cross member 11 are the upper ends of core shanks 12 and these core shanks 12 at their lower ends are provided with 55 integral cores 13 which are preferably of the shape shown.

The outer or endmost cores 13 are provided with suitable formations 14 provided for the purpose of forming the grooves 6 in the block 5, it 103 being understood that the cores 13 are used in forming the through openings 7.

In connection with the above and from a study of Figures 2 and 8 it will be seen that the formations 14 are in the form of plate-like elements 15 substantially channel shaped in end elevation.

The core shanks 12 and cores 13 are accommodated within a feed hopper 15 the walls of which are suitably inclined to insure a complete feeding 20 of the material therein toward the bottom of the hopper, and which bottom is open. The hopper 15 is rigidly supported between the standards 9 through the medium of brace arms 16.

For the bottom of the hopper 15 there is provided a valve indicated generally by the reference numeral 17.

Valve 17 is in the form of a pair of elongated plates 18—18 and these plates at one end are pivoted as at 19 to a fixed collar or flange 20 on one 30 of the standards 9 while adjacent their free ends the plates 18 rest on a support bar 21 that is secured to the standard 9 and extends laterally therefrom as clearly shown in Figure 4.

Intermediate their ends the plates 18 are com- 35 plementarily notched as at 22 to provide core accommodating openings as clearly shown in Figures 4 and 7. Manifestly with the plates 18 in the dotted line or open position shown in Figure 4 the contents of the hopper 15 will flow 403 therefrom into a mold indicated generally by the reference numeral 24.

The mold 24 is of a frame-like construction having side and end walls and accommodates 45 therein a bottom 25 provided on the upper end of a tubular shank 26 which has a sliding fit on a short post or standard 27 rising from the base 8.

The mold 24 has depending from the corners thereof guide sleeves 28 which slide upon guide standards 29 rising from the base 8, and for rais- 50 ing and lowering the mold 24 there is provided a rock shaft 30 suitably supported between the lower ends of the standards 9 and drive from the shaft 30 is transmitted to the mold 24 through the medium of toggle links 31.

A hand lever 32 is provided for rocking the shaft 30.

For transmitting upward movement of the mold 24 to the bottom member 25, the mold 24 at the corners thereof is provided with flanges 33 which, when the mold 24 is just short of the limit of its upward movement engage the bottom member 25 at the corners of the latter to cause the mold 24 to move upwardly with the mold as the mold 24 moves to the extremity of its upward motion. The object and purpose of this will be hereinafter more fully explained.

For releasably securing the mold 24 at the desired position of adjustment there is provided on the rock shaft 30 a disk 34 provided with notches 35, 36 and 37 in the periphery thereof, and cooperable with these notches is a dog 38 provided on one end of a spring arm 39 that at one end is suitably secured to the upper end of a relatively short post 40 rising from the base 8 as shown in Figure 3.

For raising and lowering the cores 13 there is provided a suitable hand lever 41 which intermediate its ends is pivoted to a bracket 42 mounted on either of two sides of the hopper 15 as suggested in Figure 3. At one end thereof the hand lever 41 has a lost motion or pin and slot connection 43 with the cross rod 11.

For releasably holding the cores 13 in the raised position shown in Figure 10 there is suitably mounted on one of the standards 9 a spring dog 44 the head 45 of which works through a suitable opening provided therefor in said one standard 9 to engage a recess 46 provided therefor in one of the guide rods 10 as clearly shown in Figure 2.

Extending laterally from one side of the mold 24 is a table 47 that is adapted to receive the block upon ejection of the block from the mold 24, and beneath the table 47 is a hood 48. Arranged within the confines of the hood 48 is a suitably mounted vibratory motor 49, the shaft of which, as clearly shown in Figure 5, is provided on the opposite ends thereof with weights 50.

For the motor 49 there is provided on the flange 20 a control switch 51 the push button 52 of which is arranged in the path of one of the plates 18 adjacent the pivoted end of said one plate as clearly shown in Figure 4. With the valve plates 18 in the closing position shown in full line in Figure 4, said one plate 18 will engage the push button 52 of switch 41 for maintaining the switch open. Consequently it will be seen that when the plates 18 are swung to the open or dotted line position shown in Figure 4 push button 52 will move outwardly to close the switch 51 and therefore complete a circuit through the motor 49 so that the latter will serve to vibrate the mold 24, this vibrating of the mold taking place during the pouring or transfer of the contents of the hopper 15 to the mold 24.

The utility and operation of the machine will be best understood from the following:

In filling the mold 24 the latter is substantially in the raised position shown in Figure 2 while the cores 13 are lowered into the mold 24 as suggested in Figure 7. Valve plates 18 are swung to the open or dotted line position shown in Figure 4 thus permitting the material to discharge from the hopper 15 into the mold 24 about the cores 13 and formers 14. In this connection it will be noted that with the valve plates 18 in open position the circuit through the motor 49 is completed so that the mold will be subjected

to a vibratory action during the filling of the mold with the contents of the hopper 15. When the proper amount of material has been fed into the mold 24 valve plates 18 are swung to the closed or full line position shown in Figure 4 thus cutting off further flow of the material from the hopper 15. The movement of the plates 18 to this closing position also results in a tripping of the switch 51 to open position so that the circuit through the motor 49 is interrupted.

In connection with the above it will be appreciated that just prior to the feeding of the contents of the hopper 15 to the mold 24 there is placed within the mold 24 to rest on the bottom 25 the pallet board 53.

Further in connection with the above it will be understood that with the mold 24 in the position shown in Figures 2 and 3 dog 38 will be engaged with the notch 35.

After the mold 24 has been filled to the proper level and the valve plates 18 moved to the closed position to cut off further flow of the contents of the hopper 15 the operator pulls downwardly on the hand lever 41 to raise the cores 12 to the position shown in Figure 2, in which position, it will be noted, the lower ends of the cores 13 are substantially flush with the closed valve plates 18. When this has been accomplished the operator then pulls on the lever 32 until notch 35 is engaged with the dog 38, this resulting in a transmission of a further upward movement of the mold 24 from the position shown in Figures 2 and 3 a distance upwardly of about one and one-half inches so that the upper edge of the mold contacts the undersides of the plates 18 which latter together with the lower surfaces of the cores 13 provide a substantially smooth top plate for the mold 24 when in this latter position for smoothing off the mold contents, and at the same time, compressing, to a certain extent, the contents of the mold.

The final operation is then to swing the lever 32 to rotate the shaft 30 in a clockwise direction (Figure 6) until dog 38 is engaged with notch 37. The rotation of the shaft 30 in this direction will result, through the medium of the links 31 in a downward movement of the mold 24 and this downward movement of the mold 24 is transmitted to the bottom member 25. When, however, the bottom 25 is in the position shown in Figure 9 mold 24 continues its downward movement until the upper edge of the walls of the mold are substantially flush with the bottom 25, and the block consequently positioned so as to be readily slid, with the pallet board 53, from off the bottom member 25 onto the shelf or table 47 whereupon the parts of the machine are in a position in order that the operation just described may be repeated for the forming of the next block.

In connection with the movement of the mold 24 from the position shown in Figure 2 upwardly to engage the closed plates 18 it will be seen, that with the flanges 33 engaging the bottom member 25 the latter will be caused to move upwardly from the position shown in Figure 2 with the mold 24 as the latter moves from the aforementioned position shown in Figure 2 to the extremity of its upward movement or, in other words, to a position engaging the undersides of the plates 18.

It will thus be seen that with a machine of this character a building block such as shown in Figure 10 may be quickly and easily made, and in actual practice it has been found that these

blocks can be made at the rate of one every ten seconds.

It is thought that a clear understanding of the construction, utility and advantages of an invention of this character will be had without a more detailed description.

Having thus described the invention what is claimed as new is:—

1. In a block making machine of the character described, a hopper, a mold arranged in alignment with the hopper, said hopper being open at its bottom, core members movable perpendicularly within the hopper and through the bottom thereof into and out of the mold, and a valve for the bottom of the hopper comprising a pair of pivoted complemental plates, said plates having complemental notches in the meeting edges thereof to provide through openings to accommodate said cores.

2. In a block making machine of the character described, a hopper, a mold arranged in alignment with the hopper, said hopper being open at its bottom, core members movable perpendicularly within the hopper and through the bottom thereof into and out of the mold, and a valve for the bottom of the hopper comprising a pair of pivoted complemental plates, said plates having complemental notches in the meeting edges thereof to provide through opening to accommodate said cores, supporting means for said cores including means for raising and lowering the cores.

3. In a block making machine of the character described, a hopper, a mold arranged in alignment with the hopper, said hopper being open at its bottom, core members movable perpendicularly within the hopper and through the bottom thereof into and out of the mold, and a valve for the bottom of the hopper comprising a pair of pivoted complemental plates, said plates having complemental notches in the meeting edges thereof to provide through openings to accommodate said cores, supporting means for said mold including means for raising and lowering the mold and away from the bottom of said hopper, and for securing the mold at the desired positions of elevation.

4. In a block making machine of the character described, a hopper, a mold arranged in alignment with the hopper, said hopper being open at its bottom, core members movable perpendicularly within the hopper and through the bottom thereof into and out of the mold, and a valve for the bottom of the hopper comprising a pair of pivoted complemental plates, said plates having complemental notches in the meeting edges thereof to provide through openings to accom-

modate said cores, supporting means for said mold including means for raising and lowering the mold and away from the bottom of said hopper, and for securing the mold at the desired positions of elevation, and a vibrator for said mold mounted on a side of said mold.

5. In a block making machine of the character described, a hopper, a mold arranged in alignment with the hopper, said hopper being open at its bottom, core members movable perpendicularly within the hopper and through the bottom thereof into and out of the mold, and a valve for the bottom of the hopper comprising a pair of pivoted complemental plates, said plates having complemental notches in the meeting edges thereof to provide through openings to accommodate said cores, supporting means for said mold including means for raising and lowering the mold and away from the bottom of said hopper, and for securing the mold at the desired positions of elevation, and a vibrator for said mold mounted on a side of said mold, said vibrator including an electric motor, a control switch for said motor, and said control switch being mounted between the plates of said valve and having a push button in the path of one of said plates to be engaged thereby for opening the switch incidental to a movement of the valve plates to a closing position.

6. In a block forming machine of the character described, a hopper, posts at opposite sides of said hopper, rods having a sliding fit in said posts, a cross bar connecting the rods at one end of the latter, a plurality of rigid shanks depending from said cross bar and extending into said hopper, core members on the shanks at the lower ends of the latter, and formers on the endmost core members for giving a predetermined shape to the respective opposite ends of a block to be formed in said machine.

7. In a block forming machine of the character described, a hopper, posts at opposite sides of said hopper, rods having a sliding fit in said posts, a cross bar connecting the rods at one end of the latter, a plurality of rigid shanks depending from said cross bar and extending into said hopper, core members on the shanks at the lower ends of the latter, and a valve for the bottom of said hopper including a pair of complemental plates hinged at one end for movement toward and away from one another, and said plates being complementarily notched to provide through openings for accommodating said core members when the plates of said valve are in a closed position.

JOSEPH J. HOLLAND, JR.
